UNITED STATES PATENT OFFICE.

THOMAS A. KRIESEL, OF CHICAGO, ILLINOIS.

TROUSERS-PRESSER.

1,356,724.

Specification of Letters Patent. Patented Oct. 26, 1920.

Application filed February 13, 1920. Serial No. 358,377.

To all whom it may concern:

Be it known that I, THOMAS A. KRIESEL, a citizen of the United States, residing at Chicago, county of Cook, and State of Illinois, have invented new and useful Improvements in Trouzers-Pressers, of which the following is a specification.

This invention relates to improvements in pressing devices for garments, and particularly to improvements in pressing devices for trousers.

It is an object of the invention to provide a device by which the main portion of the garment may first be adjusted to flat condition, combined with means for firmly gripping a marginal portion of the garment so that afterward the main portion of the garment can be finally adjusted and pressed.

It is also an object of the invention to provide a device in which the pressure exerted upon different portions of the garment may be adjusted independently of the pressure upon other portions.

It is also an object of the invention, in applying the device to the pressing of trousers, to put more pressure on the cuffs than on the rest of the trousers, and to provide a somewhat greater space for the reception of these cuffs than for the portions of the garment which have not the same thickness.

Additional objects of the invention will become apparent from the following specification and the appended claims, the invention being illustrated in the accompanying drawing, wherein—

Figure 1 is a top plan view of the pressing device;

Fig. 2 is a top plan view, in a larger scale, of the portion of the device, with certain parts being shown broken away;

Fig. 3 is a sectional view on line 3—3 of Fig. 1, on a larger scale;

Fig. 4 is a section through the device, also on a larger scale, on line 4—4 of Fig. 1, and

Figs. 5 and 6 are enlarged sectional detail views on lines 5—5 and 6—6 of Fig. 2.

The device comprises two pressing members or boards 1 and 2, which have approximately the outline of the garment to be received between, as, for instance, a pair of trousers. These pressing members are reinforced at intervals by cross strips 3, 4, and 5, which extend transversely of the members, and which at the same time serve for receiving the clamping means.

The cross strips 3, 4, and 5 are provided

with metal plates 6 and 7, respectively; the upper plates 6 being secured to the upper cross strips 3, 4, and 5, and being provided with slots 10, which extend from the outer edges of these plates inwardly. Similar slots in registration with the slots 10 also extend through the cross strips and through the pressing members 1 and 2. The lower plates 7, secured to the transverse reinforcing strips, carry near their front ends hinge pins 11, to which bolts 12 are pivotally secured. The bolts are mounted on these pins to swing within the registering slots 10 in the pressing members and reinforced plates. By means of wing nuts 13 engaging these bolts, the pressing members may be forced together with adjustable pressure, or, after the wing nuts are loosened, the bolts may be swung outwardly in the slots and the pressing members may be separated.

The upper board or member 1 engages at its lower surface a metal plate 15, to which are riveted the pins 16, slidable in holes 17 in the member 1 and provided with heads 18, which are movable in suitable openings 19 in the cross strips.

Springs 20, inserted between the cross strips and the plate 16 in suitable openings 21 of the upper pressing member, have a tendency to force this plate down or away from the lower surface of the board 1.

Additional clamping means, which, in the present embodiment, are shown as intended to operate on the cuffs of the trousers, are particularly illustrated in Figs. 4, 5, and 6. Transverse strips 22 and 23 are inserted into the pressing members 1 and 2 near their ends and parallel to the reinforcing strips 3, 4, 5. These inserted strips 22 and 23 are provided with tapped openings 24 to receive the ends of pressure screws 25, which project outwardly from the margin of the board, and which are provided at their projecting ends with heads 26 and handles 27 to facilitate the rotation of the screws by hand. These screws also extend through wedge-shaped strips 28 and 29, respectively, having their outer surfaces parallel to the surfaces of the pressing boards, which have reduced marginal portions 1', 2', and the inner surfaces of these wedge strips are in coöperation with additional wedge blocks or strips 31 and 32, which are united with the pressing members 1 and 2, as clearly shown in Figs. 4 and 6.

The wedge strips 31 and 32 are provided with metal plates 33, to which are riveted

pins 34, extending through the coöperating wedge blocks 28 and 29, and through the reduced portions 1', 2' into suitable openings 35 of the corresponding reinforcing strips 6 and 7. The outer wedge blocks 28 and 29, through which these holding pins 34 for the lower wedge blocks 31 and 32 pass, are provided with longitudinal slots 36 to permit their displacement with respect to the pressing members 1 and 2 and with respect to the outer wedge blocks 31 and 32 in longitudinal direction. By rotation of the pressure screws 25 the coöperative wedge blocks 28 and 31, 29 and 32, are relatively displaced by movement of the outer wedge blocks 28 and 29, with respect to the inner blocks 31 and 32, and the inner wedge blocks 31 and 32 may thereby be forced against each other with great pressure, at the same time, however, maintaining parallel relation to each other.

The operation of the device is as follows:

After the garment has been laid flat on the top surface of the lower pressing member 2, the upper pressing member 1 is applied and brought into registration with the lower member. The springs 20 will have a tendency to force the plate 15 into contact with the garment so as to prevent displacement of the same. The end portion of the garment, gripped between the inner faces of the wedge members 31 and 32, is firmly pressed together by suitable adjustment of the pressure screws 25, and after this end portion has been firmly gripped, the other part of the garment may be pulled taut so as to place the garment absolutely into flat condition. The wing nuts 13 are then tightened upon the bolts 12 and the pressure may either be uniformly distributed or adjusted to different degrees at different portions of the garment.

I claim:

1. In a device of the character described, the combination of pressing members, means for forcing them together, and additional means for clamping garment portions between them, said additional means being supported by said pressing members, and being operative in a direction at right angles to the first named means for forcing the pressing members together.

2. In a device of the character described, the combination of a pair of pressing members, means for forcing them together, a pair of coöperative wedge members in each pressing member, and means for longitudinally displacing said coöperative wedge members relatively to each other, and for decreasing the distance between the sets of wedge members carried by the pressing members.

3. In a device of the character described,

the combination of pressing members, means for forcing them together, and a set of coöperative wedge members in a pressing member, one of said wedge members being slidably supported in the pressing member, the other wedge member being slidably supported between the pressing member and the first named wedge member, and means for longitudinally displacing said second wedge member with respect to said pressing member.

4. In a device of the character described, the combination of a pair of pressing boards, means for forcing them together, a wedge member, pins traversing the pressing board and supporting at their free end said wedge member, a companion wedge member provided with longitudinal slots through which said pins extend, and means for longitudinally displacing one of said wedge members with respect to the other.

5. In a device of the character described, the combination of a pair of pressing boards, means for forcing them together, and a plate yieldingly held in connection with one of said pressing boards and adapted to maintain a garment in flat condition between said pressing boards prior to the application of pressure on said pressing boards.

6. In a device of the character described, the combination of a pair of pressing boards, means for forcing them together, pins passing through one of said pressing boards, a plate fastened to said pins, and means for normally urging said plate away from the pressing board to which it is secured.

7. In a device of the character described, the combination of a pair of pressing boards, means for forcing them together, pins slidably extending through one of said pressing boards, a plate fastened to said pins, and springs inserted in said pressing board and acting upon said plate, adapted to force said plate normally away from said pressing board in direction toward the other pressing board when the parts are in operative position.

8. In a device of the character described, the combination of a pair of pressing boards, means for forcing them together, a plate connected to one of said pressing boards, means for normally urging said plate away from said pressing board, and means for limiting the movement of said plate away from said pressing board.

In testimony whereof, I have affixed my signature at 36 W. Randolph street, in the presence of two witnesses.

THOMAS A. KRIEGEL.
